UNITED STATES PATENT OFFICE.

MARTIN HINES, OF BROOKLYN, NEW YORK.

PUZZLE.

1,173,271.

Specification of Letters Patent.

Patented Feb. 29, 1916.

Application filed December 7, 1915. Serial No. 65,494.

To all whom it may concern:

Be it known that I, MARTIN HINES, a citizen of the United States, and residing at Brooklyn, in the county of Kings and State 5 of New York, have invented certain new and useful Improvements in Puzzles, of which the following is a specification, such as will enable those skilled in the art to which it appertains to make and use the 10 same.

This invention relates to puzzles, and the object thereof is to provide an improved device of this class which is simple in construction and difficult of solution, but the 15 solution of which may be accomplished by the exercise of care and skill in the manipulation of the device; a further object being to provide a device of the class specified which will serve as an amusement for both 20 old and young; and with these and other objects in view the invention consists in a puzzle constructed, as hereinafter described and claimed.

The invention is fully disclosed in the 25 following specification, of which the accompanying drawing forms a part, in which the separate parts of my improvement are designated by suitable reference characters in each of the views, and in 30 which:—

Figure 1 is a plan view of my improved puzzle; and, Fig. 2 a central longitudinal section on the line 2—2 of Fig. 1.

In the practice of my invention, as shown 35 in the drawing, I provide an oblong and rectangular box *a* having a slide cover *b* which may be manipulated in the manner of other devices of its class, and to the bottom of the box *a* at one end thereof is secured 40 a transverse plate *c* which serves as a raised bottom portion. Arranged transversely of the bottom of the box *a* and nearer the plate *c* than the opposite end of said box is a fulcrum *d* on which is pivoted a board *e*, and the end *e*² of the board *e* is slightly 45 longer than the end portion *e*³ whereby the end portion *e*² of said board will normally rest in the position shown in full lines in Fig. 2.

The board *e* is pivoted to and on the fulcrum *d* in the construction shown by means of headed pins or nails *f* driven into the opposite sides of said board, and staples *g* driven into said fulcrum and through 55 which the pins or nails *f* pass, but my invention is not limited to any particular

means for pivoting the board *e* in connection with the fulcrum *d*. The board *e* is provided with a central longitudinal groove *e*⁴ provided, in the construction shown, with 60 beveled side walls *e*⁵, and this groove opens through the end portion *e*³ of said board but is beveled outwardly at the end portion *e*² so that the bottom wall thereof is flush with the top surface of the plate *c* as shown 65 at *e*⁶. The board *e* is also provided, in the groove *e*⁴, with equally spaced recesses *e*⁷, *e*⁸ and *e*⁹, the recess *e*⁸ being in transverse line with the pivotal supports of said board and the other recesses being adjacent to the 70 opposite ends thereof, and said recesses are provided with concave bottoms and are adapted to receive balls *h*, three of which are employed.

The front side edge portions of the plate *c* are beveled backwardly as shown at *c*² so as to permit the balls *h* to roll freely from the bottom of the box *a* onto said plate *c* in the manipulation of the device, as hereinafter described, but the top surfaces of the side portions of the board *e* at the end *e*² thereof are flush with the top surface of the plate *c* as shown at *i*, when said board *e* is in the position shown in full lines in Figs. 1 and 2. 85

The top surface of the bottom of the box *a* is smooth and even throughout and the balls *h* are free to roll thereover, and the solution of the puzzle consists in manipulating said box so as to lodge the three 90 balls *h* in the recesses *e*⁷, *e*⁸ and *e*⁹ in the bottom of the groove *e*⁴ of the board *e*. This solution is very difficult, in view of the fact, that said board is free to swing on the fulcrum *d* and the further fact that the end 95 portion *e*² of the board is slightly heavier than the opposite end portion, and when the box is held horizontally, or placed on a support of any kind, the normal position of the board *e* is that shown in full lines 100 in Figs. 1 and 2.

In the solution of the puzzle, the box is manipulated so as to roll one of the balls into the recess *e*⁸, another into the recess *e*⁹ and the third into the end of the groove 105 *e*⁴ of the board *e* adjacent to the plate *c*, after which the box is further manipulated so as to roll the ball in the recess *e*⁸ into the recess *e*⁷ and the ball in the recess *e*⁹ into the recess *e*⁸, and the ball in the end of the 110 groove *e*⁴ adjacent to the plate *c* into the recess *e*⁹. This solution is difficult, especially

to a beginner, but may be accomplished by the exercise of care and skill and after experience in connection with the manipulation of the box for the purpose of solving 5 the puzzle, as above set out, the said solution becomes quite simple.

The solution of the puzzle is not limited to the exact method of manipulating the box hereinbefore described, and other 10 methods may be adopted, nor is the invention limited to the exact details of construction herein shown and described. The bottom of the box on which the plate *c* is placed may be raised in any way, and the 15 box may be of other forms, and the board *e* may be pivoted in said box in any desired manner, and other changes in and modifications of the details of construction herein shown and described, including those of the 20 box and its cover may be made, within the scope of the appended claims, without departing from the spirit of my invention, or sacrificing its advantages.

Having fully described my invention, 25 what I claim as new and desire to secure by Letters Patent, is:—

1. A puzzle, comprising a box, the bottom of which at one end thereof is raised, a board pivoted between the raised portion 30 of the bottom and the opposite end portion of the box, and the end of which adjacent to the raised portion of the bottom of the box is slightly heavier than the opposite end portion, said board being provided 35 with a central longitudinal groove in the bottom of which are a plurality of recesses adapted to receive a corresponding number of balls placed in said box.

2. A puzzle device of the class described, 40 comprising an oblong rectangular box one end portion of the bottom of which is raised, and a board pivoted transversely of said box between the raised end of the bottom and the opposite end portion of the box, 45 the end portion of said board adjacent to the raised bottom of the box being slightly heavier than the opposite end portion, and

said board being provided in the top surface thereof with a longitudinal groove in the bottom of which are equally spaced recesses, one of which is in transverse line with the pivotal supports of said board. 50

3. A puzzle device of the class described, comprising an oblong rectangular box one end portion of the bottom of which is raised, 55 a board pivoted transversely of said box between the raised end of the bottom and the opposite end of the box, the end portion of said board adjacent to the raised bottom of the box being slightly heavier than the 60 opposite end portion, and said board being provided in the top surface thereof with a longitudinal groove in the bottom of which are equally spaced recesses, one of which is in transverse line with the pivotal supports 65 of said board, and a plurality of balls placed in said box.

4. A puzzle, comprising a box, the bottom of which is provided with a raised portion, a member pivoted in said box and adapted 70 to operate in connection with said raised portion, and said member being provided in the top face thereof with a groove and recesses in connection with which a plurality of spherical members are adapted to 75 operate.

5. A puzzle comprising a box the bottom of which is provided with a raised portion, a member pivoted in said box and adapted to operate in connection with said raised 80 portion, said member being provided in the top face thereof with a groove in which is formed a plurality of recesses adapted to receive a corresponding number of balls placed in said box. 85

In testimony that I claim the foregoing as my invention I have signed my name in presence of the subscribing witnesses this 3rd day of December, 1915.

MARTIN HINES.
